His Attorney.

UNITED STATES PATENT OFFICE

2,092,274

AUTOMATIC STOKER

William M. Duncan, Alton, Ill.

Application July 16, 1934, Serial No. 735,354

6 Claims. (Cl. 110—104)

This invention pertains to stokers of the type employing a blast of steam or the like to deliver the fuel to the fire bed.

One of the objects of this invention is to provide a stoker of this type which will deliver the fuel in such a manner as to form a uniform bed over the entire grate.

Another object is to provide such a stoker in which the action may be adjusted so as to vary the manner in which the fuel is distributed.

Another object of this invention is to provide novel mechanism by which the movement of the distributing parts may be adjusted and controlled.

Further objects will appear from the following description taken in connection with the accompanying drawing in which:—

Figure 1 is a side view partly in section of a stoker embodying this invention;

Figure 2 is a section taken about on line 2—2 of Figure 1;

Figure 3 is an enlarged detail of Figure 2; and

Figure 4 is a detail of Figure 1, showing the nozzle extended and the deflector plate in expanded relation with the blast tube and the nozzle.

In the following description, that end of the apparatus which is projected into the furnace is considered the forward end for the purposes of the description and claims.

In accordance with this invention the fuel is injected into the furnace by being passed through an injection tube by means of a steam jet. The end of the tube is provided with a nozzle which may be directed toward different parts of the furnace grate and is adapted to deflect the fuel and direct it to corresponding parts of the grate. Mechanism is provided for moving the tube and its nozzle progressively in a definite cycle so that the fuel is deposited on different parts of the grate in a progressive manner so as to cover the entire grate.

Referring now to the drawing, 1 designates the furnace wall having an opening 2 through which the injection tube may enter the furnace. The grate is indicated at 3.

A suitable support 4 is provided which may be mounted outside the furnace adjacent the wall 1 so as to support the stoker mechanism. In the embodiment illustrated the support 4 is constructed as a frame work of angle iron.

Mounted in the upper part of the frame work 4 is a pair of supporting rings 5. These are each provided on its inner surface with a rib or track 6. A blast tube 7 is provided with rollers 8 sup-

ported in the rings 5 and having grooves adapted to run on the tracks 6. In this manner the tube 7 is supported in the rings 5 for rotary rocking movement on its axis. Secured to the tube 7 is an arm 9 by means of which the tube 5 may be rocked on its axis.

In order to actuate the tube a motor 10 is connected by a belt 11 to drive the shaft 12 carrying a pulley 13 connected by a belt 14 to drive a shaft 15 of a speed changing mechanism 10 16. The speed changer 16 has two low speed shafts, one of which 17 is connected to operate the mechanism for rocking the tube. The shaft 17 carries a crank or eccentric 18 having a strap 19 on the end of a connecting rod 20. The rod 20 is adjustable in length in any suitable manner and carries at its upper end a fork 21 pivoted to a collar 22 adjustable along an arm 23 pivoted on a shaft 24. The arm 23 carries a pawl 25 engaging a ratchet wheel 26 on the shaft 24. The ratchet wheel 26 is provided with a plurality of perforations 27 providing sockets for a pivot pin 28 for a link 29 pivoted at its other end to the free end of the arm 9.

By the operation of this mechanism the eccentric 18 acting through the rod 20 rocks the arm 23 about the shaft 24. This arm acting through the pawl 25 rotates the ratchet wheel 26 which in turn provides a crank mechanism for reciprocating the link 29. The link 29 swings the arm 9 up and down and thereby rocks the tube 7 in its bearing rings 5. The throw of the crank mechanism is adjustable by changing the pivot pin 28 to different holes 27, said holes being located at different radii with respect to the shaft 24. By adjusting the collar 22 along the arm 23 the extent of movement given by the pawl 25 to the ratchet wheel 26 at each stroke may be adjusted. Accordingly, both the extent of the rocking movement of the blast tube and also the rapidity of such movement may be adjusted at will.

The tube 7 extends through the opening 2 to the interior of the furnace and is provided at its inner end with a nozzle 31 pivoted at 32 on a bracket 33 carried by the tube 7. This pivotal mounting provides that the nozzle 31 may be swung outwardly or inwardly so as to direct the blast toward any portion of the grate 3. The nozzle 31 has a loose section 34 pivoted at 35 to the nozzle itself. The rear portion of the section 34 is provided with a roller 36 adapted to run in a groove 37 extending along the upper portion of the tube 7. The nozzle 31 is provided at the inner end thereof with a pin 39. This pin provides a

- 5 pivotal connection to an adjustable link 40 which link is pivoted at 41 to a bracket 42 extending forwardly from an actuating ring 43. The ring 43 surrounds the tube 7 and is provided with 5
 10 grooved rollers 44 running on tracks 45 mounted to extend along the tube 7 at the rear portion thereof. These connections are such that by moving the ring 43 rearwardly along the tube 7 the link 40 acts to pull on the pin 39 thereby 10
 15 tilting the nozzle 31 upwardly on its pivot 32. During such movement the loose section 34 hinges at 35, the roller 36 moving rearwardly in the groove 37. The link 40 and its connections may be duplicated on the opposite side of the tube 7.
 15 The loose section 34 is provided with a pin 38 adapted to engage a hook 71 on the end of the link 40, which prevents said section from tilting up on the pivot 35.
 20 This arrangement provides a variable telescopic engagement between the tube and its nozzle so as to insure proper functioning in all positions. The section 34 takes an expanded position with reference to the nozzle 31 when the latter is tilted upwardly.
 25 The actuating ring 43 is operated by the following mechanism. The second low speed shaft of the speed changer 16 is indicated at 46, see Figure 2. This shaft carries a crank 47 connected by an adjustable link 48 to a collar 49 adjustable 25
 30 along an arm 50. The arm 50 is fixed to a rock-shaft 51 journaled in suitable bearings on the frame 4 and carrying a pair of arms 52 of a fork embracing the ring 43 having at their upper ends inwardly directed pins engaging in a groove 53 in the actuating ring 43. It will be seen that by this mechanism the operation of the shaft 46 will act through the link 48 and the arm 50 to rock the shaft 51. Said shaft in turn rocks the arms 52 and said arms operate to move the ring 43 35
 40 rearwardly and forwardly along the tube 7, the rollers 44 moving along the tracks 45 during such movement. The extent of this movement can be adjusted by adjusting the collar 49 along the arm 50.
 45 The mechanism just described operates to tilt the nozzle 31 on its pivot 32. This movement changes the direction of the nozzle 31 from front to rear of the grate 3 so that fuel issuing therefrom will be deposited progressively along the 45
 50 depth of the grate. The rocking movement of the tube 7 on its axis takes place simultaneously so that as the nozzle 31 is swung forward and rearward, the tube 7 is gradually rocked. Accordingly the successive swings of the nozzle will deposit the issuing fuel along paths progressively spaced from one another laterally of the grate 3. As these movements take place in a definite cycle, it will be seen that the fuel is deposited progressively along different portions of the grate so that 55
 60 the entire grate is covered. The regularly repeated cycles of movement may be so adjusted that a uniform bed of fuel is produced and maintained on the grate 3.
 In order to propel the fuel along the tube 7 a jet 54 for steam or the like is directed along the tube 7 from the rear end thereof. This jet may be connected by a pipe 55 to a suitable source of supply, not shown.
 65 Mounted opposite of the rear end of the tube 7 is a fuel feeding conveyor 56 adapted to receive fuel such as coal from a hopper 57 and to deliver the same in front of the jet 54. The conveyor 56 may be driven through a suitable gear box 58 connected by a belt 59 to a suitable speed controlling device 60 illustrated in the drawing as
 70

of the well known Reeves transmission type, comprising a pair of V-groove pulleys having flanges oppositely adjustable to vary the operating radius of a connecting V-belt 75 also driven by the motor 10 thru belt 11 and shaft 12. This provides for suitably controlling the rate of feed of the fuel so as to control the action of the furnace. 5

In the embodiment illustrated the hopper 57 is designed for coal and is arranged so that the coal is delivered to the blast tube by feeding it so as to cause it to drop in front of the jet 54, an opening being maintained over the coal for the entrance of air to assist in carrying the fuel through the blast tube and for combustion 10
 15 thereof. 15

In order to stop the operation of the stoker when the motor 10 is stopped, the steam line 55 may be provided with a shut off valve 61. This valve may be connected with any suitable device 20 for closing it automatically when the motor 10 is stopped, as for instance, a solenoid 64, through which the current of the motor 10 is passed, and so connected to the valve that when the solenoid is energized by the flow of current it will hold the valve open, the valve being weighted or otherwise actuated to close when the solenoid is de-energized by opening the motor circuit L. 25

The blast tube 7 may be provided with perforations 70 near its rear end, positioned so that the 30 aspirating action of the jet 54 will draw in air which assists in carrying the fuel along the tube. Such air is delivered to the fire box with the fuel to take part in the combustion thereof. 35

It will be seen that this invention provides a 35 stoker of simple construction which is effective in operation and flexible in its adjustment making it adaptable to a variety of firing conditions. The tube 7 is rockable upon its axis and is provided with an articulated nozzle movable on the 40 tube itself. The movements of the tube and the nozzle may be varied relatively to each other so as to vary the cycle of movement of the nozzle in order to control the manner in which the fuel is distributed upon the grate. The actuating 45 mechanisms are simple and easily adjusted. The entire stoker is so arranged that it may be built up as a unit and applied to any existing furnace by simply mounting the same in front of the furnace and inserting the blast tube through a 50 suitable opening in the furnace wall. 55

While this stoker has been described as a unitary device it will be understood that individual features or sub-combinations thereof may be useful by themselves without reference to other 55 features or the complete combination and it is understood that the employment of such individual features or sub-combinations is contemplated by this invention and within the scope of the appended claims. 60

It is obvious that various changes may be made, within the scope of the appended claims, in the details of construction without departing from the spirit of this invention. It is to be understood, therefore, that this invention is not limited to the specific details shown and/or described. 65

Having thus described the invention, what is claimed is:

1. In a stoker of the character described, a 70 blast tube adapted to be extended into the furnace and a nozzle tube hinged at its lower edge to said blast tube, said nozzle tube comprising a main body portion and an upper wall portion hinged to said body portion and freely engaging 75

said blast tube at its free end to permit swinging said nozzle tube through substantially a right angle.

2. In a stoker of the character described, a blast tube adapted to be extended into the furnace at a substantial elevation above the grate thereof and a nozzle tube hinged at its lower edge to said blast tube, said nozzle tube comprising a main body portion and an upper wall portion hinged to said body portion and freely engaging said blast tube at its free end to permit swinging said nozzle tube downwardly at an angle such as to deposit the fuel at the front of the grate.

3. In a stoker of the character described, a blast tube adapted to be extended into the furnace, a nozzle tube at the inner end of said blast tube arranged to form an extension thereof, means swingably supporting said nozzle tube for movement to various positions relative to said blast tube, said nozzle tube having a wall portion thereof free for movement relative to said nozzle tube, means swingably supporting said wall portion adjacent the juncture of said nozzle and said blast tube, and means on said wall portion engaging one of said tubes adapted to position said wall portion to form with said tubes a substantially continuous tubular guide for the fuel in all positions of said nozzle tube.

4. In a stoker of the character described, a blast tube adapted to be extended into the furnace, a nozzle tube at the inner end of said blast tube arranged to form an extension thereof, means swingably supporting said nozzle tube for movement to various positions relative to said blast tube, a wall portion arranged in continuity with said nozzle tube and free for movement rela-

tive to said nozzle tube, means swingably supporting said wall portion on one of said tubes, and means on said wall portion engaging the other of said tubes adapted to position said wall portion to form with said tubes a substantially continuous tubular guide for the fuel in all positions of said nozzle tube.

5. In a stoker of the character described, a blast tube adapted to be extended into the furnace, a nozzle tube swingably supported at the inner end of said blast tube for movement to various positions in angular extension of said blast tube, and a wall section movably mounted in continuity with said tubes adjacent the juncture thereof and means engaging said tubes to position said section in bridging relation thereto for guiding the blast from said blast tube to said nozzle tube.

6. In a stoker of the character described, a blast tube adapted to be extended into the furnace, a nozzle tube at the inner end of said blast tube, means swingably supporting said nozzle tube for movement to various positions relative to said blast tube in angular extension thereof, a wall section free for movement relative to said tubes, means swingably supporting said section on one of said tubes, said section being in continuity with one of said tubes adjacent the juncture thereof, and means on said section engaging the other of said tubes, said supporting and engaging means being constructed and arranged to position said section intermediate said tubes to provide a guide adapted to direct the blast from said blast tube to said nozzle tube.

35 WILLIAM M. DUNCAN.
